CLAIM

We claim the ornamental design for a rotor for tractor-towed agricultural implement, as shown and described.

DESCRIPTION

FIG. 1 is a right perspective view of a rotor for tractor-towed agricultural implement showing our new design;

FIG. 2 is a right side elevation view thereof;

FIG. 3 is a rear elevation view thereof;

FIG. 4 is a front elevation view thereof;

FIG. 5 is a top plan view thereof;

FIG. 6 is a bottom plan view thereof; and,

FIG. 7 is a left side elevation view thereof.

Broken lines in the drawings represent unclaimed environmental subject matter and form no part of the claimed design.
